UNITED STATES PATENT OFFICE.

UTLEY WEDGE, OF ARDMORE, PENNSYLVANIA.

METALLURGICAL FURNACE.

1,131,449.

Specification of Letters Patent.

Patented Mar. 9, 1915.

Application filed July 16, 1913. Serial No. 779,260.

To all whom it may concern:

Be it known that I, UTLEY WEDGE, a citizen of the United States, residing in Ardmore, Pennsylvania, have invented certain 5 Improvements in Metallurgical Furnaces, of which the following is a specification.

My invention relates to that class of metallurgical furnaces which are intended for roasting or otherwise treating finely divided 10 ore or other material (hereinafter, for convenience, referred to as "ore"). Such furnaces usually have superposed hearths and the ore passes downwardly from hearth to hearth throughout the series.

15 The object of my invention is to provide means whereby the ore may be permitted to pass from an upper to a lower hearth while at the same time the upward passage of gas from the lower to the upper chamber is restricted or prevented. This object I attain 20 in the manner hereinafter set forth, reference being had to the accompanying drawing, in which—

Figure 1 is a vertical sectional view of 25 sufficient of a furnace of the type to which my invention relates to illustrate the application of one form of my invention thereto; Figs. 2, 3 and 4 are transverse sections on the line *a—a*, Fig. 1, and on a larger scale, 30 illustrating different positions of the controlling valve; Fig. 5 is a view similar to Fig. 1, but illustrating a different embodiment of my invention; Fig. 6 is a plan or top view of part of the furnace shown in Fig. 5, and Fig. 7 is a side view showing in 35 different positions one of the valve-operating levers shown in Fig. 5.

In the drawing, 1, 2, 3 and 4 represent successive hearths of the furnace, and 5, 6, 40 7 and 8 successive treating chambers thereof, the hearths being supported upon an outer wall 9 and having central openings for the reception of a central rotating shaft 10 which is provided with radiating arm 11 intended 45 for the reception of the usual rabbles, whereby the ore on the hearth beneath is stirred or agitated and fed over the hearth. Some of the hearths are provided with passages 12 at or near the outer periphery of the hearth 50 and alternate hearths are provided with passages 13 at the inner periphery, the rabbles being so constructed as to feed the ore outwardly on those hearths which have the outer passages 12 and inwardly on those 55 hearths which have the inner passages 13,

whereby the ore is caused to pass in a zig-zag course throughout the furnace.

In the present instance I have shown my improved controlling valve as applied to the outer passages only, although the inner 60 passages may also be constructed for the reception of controlling valves, if desired. The valve 14 shown in Figs. 1 to 4 is a hollow cylindrical valve with an opening 15 at one side so as to constitute a pocket which 65 may be caused to communicate with the upper portion of the passage 12 in the hearth in order to receive the ore therefrom, as shown in Fig. 2, or with the lower portion of said passage so as to discharge the ore 70 contained in the valve onto the hearth below, as shown in Fig. 4, the dimensions of the opening 15 being such that the top portion of the passage 12 will, as shown in Fig. 3, be closed by the valve before the opening of 75 the lower portion of said passage, so that at no time is any passage afforded for flow of gas from a chamber beneath the valued hearth to that above the same.

The valve 14 is mounted in a casing 16 80 which, by preference, extends across the opening 12 and through the outer portion of the hearth and the outer wall 9, as shown in Fig. 1, so that the casing and the valve contained therein can be readily introduced 85 or removed from the outside of the furnace, provision being thereby afforded for the ready renewal of any valve which may become defective for any reason. The outer end of the casing 16 is closed by a cover 90 plate 17 which has a bearing for a shaft 18 whereby the valve may be readily turned. The uppermost hearth 1 of the furnace is ordinarily utilized as a drying hearth for the ore preparatory to its introduction into 95 the uppermost treating chamber 5 and the valve 14 in said upper hearth prevents the escape of any gases introduced into or generated in said uppermost chamber 5 while the valve in the hearth 3 in like manner 100 prevents the passage of gases from the treating chamber 7 into the treating chamber 6.

In the furnace shown in the drawing the chambers 5 and 6 and the chambers 7 and 8 are in communication with each other 105 through the inner passages 13 but as before stated each chamber may be independently sealed by so constructing said passages 13 as to provide for the use of valves 14 therein.

Any desired means may be employed for 110

imparting movements of rotation or partial rotation to the valves 14, the means employed in the present instance for this purpose being as follows: Mounted in suitable 5 bearings on the outside of the furnace is a vertical shaft 19 which is geared by bevel wheels 20 and 21 to each of the valve shafts 18 and is also provided with a bevel wheel 22 meshing with a bevel wheel 23 on a shaft 10 which is mounted in a suitable bearing 24 on the top of the wall 9 and is provided at its inner end with projecting arms 25, adapted to be struck in succession by a projecting lug 26 at the outer end of each of the 15 uppermost rabble arms 11, whereby, as the latter rotate with the shaft 10, the shaft carrying the bevel wheel 23 will have intermittent movements of partial rotation imparted to it, which movements will be transmitted 20 through the bevel wheel 22 to the shaft 19 and thence through the bevel wheels 20—21, to the valve shafts 18 so as to cause either a complete or partial rotation of each of the valves 14.

25 My invention can be adopted in connection with a furnace of any desired height and having any desired number of superposed hearths.

In Figs. 5, 6 and 7 I have illustrated a 30 furnace provided with swinging valves in accordance with my invention in place of the rotating valves shown in Figs. 1 to 4. These swinging valves are indicated at 30 and when in one position extend across the 35 openings 12, as shown in Fig. 5, so as to obstruct the passage of ore therethrough but when swung downwardly from this position permit of the flow of ore through the opening 12 from an upper to a lower hearth. 40 The valves 30 are carried by rock shafts 31 mounted in bearings 32 on the outside of the furnace, each of these rock shafts also having an arm 33 which is connected by a rod 34 to one arm of a lever 35 pivotally 45 mounted in a bearing 36 at the top of the furnace, the other arm of said lever 35 being acted upon by an anti-friction roller 37 mounted so as to rotate in the upstanding end 38 of one of the rabble arms 11 at the 50 top of the furnace. That arm of the lever 35 on which the roller 37 acts is bent so as to normally project into the path of said roller, as shown by full lines in Fig. 7, whereby when said arm is struck by the 55 roller it is depressed, as shown by dotted lines in Fig. 7, so as to raise the rod 34 and

arm 33 and thereby swing the valve 30 from the closed position represented by full lines in Fig. 5 to the open position represented by dotted lines in said figure, thereby permitting the ore which has accumulated in the opening 12 and on the hearth above said opening to slide from the upper face of the valve and onto the hearth beneath, the valve being opened to such a limited extent or remaining in the open position for such a limited time that the flow of ore acts as a lute for the opening 12 to substantially cut off the upward passage of gas therethrough.

The closing of the valve when the lever 70 35 is freed from the influence of the roller 37 is effected by means of a weight 39 hung to the arm 33 or to the lower end of the rod 34, as shown in Fig. 5.

I claim:

1. A furnace having a series of superposed hearths with working chambers above the same, each of said hearths having a valved passage therethrough for permitting flow of ore from the chamber above the 80 hearth to that below the same, a rotary shaft having thereon arms located above the topmost hearth of the furnace, and means whereby the valves of the various hearths can be opened and closed by said arms. 85

2. A furnace having a series of superposed hearths with working chambers above the same, passages through the hearths each having therein a valve which can be moved to open or close the passage, and means for connecting the valves of the different hearths for joint and simultaneous operation.

3. A furnace having a series of superposed hearths with working chambers above the same, said hearths having therein passages through which ore can flow from an upper to a lower chamber, valves in said passages which at all times seal the same against upward flow of gas through the 95 passages, a rotating shaft carrying rabble arms disposed in the working chambers of the furnace, and means carried by said shaft for effecting the operation of the valves in the hearth passages at predetermined intervals. 100

In testimony whereof, I have signed my name to this specification, in the presence of two subscribing witnesses.

UTLEY WEDGE.
